D. A. LIVINGSTON

NEEDLE THREADING ATTACHMENT

Filed July 19, 1920

Patented Mar. 4, 1924.

1,485,684

UNITED STATES PATENT OFFICE.

DAVID ALEXANDER LIVINGSTON, OF METCHOSIN, BRITISH COLUMBIA, CANADA.

NEEDLE-THREADING ATTACHMENT.

Application filed July 19, 1920. Serial No. 397,536.

To all whom it may concern:

Be it known that I, DAVID ALEXANDER LIVINGSTON, a subject of the King of Great Britain, and a resident of the Post Office 5 of Metchosin, in the Province of British Columbia, Canada, have invented certain new and useful Improvements in Needle- Threading Attachments, of which the following is the specification.

- 10 The invention relates to improvements in needle threading attachments and particularly for use on sewing machines wherein there is a comparatively small eye in the needle and an object of the invention is to 15 provide a simply constructed inexpensive and durable device which can be readily attached to the needle and by the use of which one can quickly and positively thread the needle.
- 20 A further object of the invention is to construct the appliance from as few parts as possible and so that it can be fitted to the varying existing types of needles and also so that it can be adjusted on the needle 25 to accommodate the threader to the needle eye.

A still further object is to arrange the appliance so that it can be quickly thrown to "non-use" or "set" position. With the 30 above more important objects in view, the invention consists essentially in the arrangement and construction of parts herein- after more particularly described and later 35 pointed out in the appended claim reference being had to the accompanying drawing in which—

Fig. 1 is a side view of the foot end of a sewing machine and showing my appliance attached to the needle.

40 Fig. 2 is an enlarged side view of the attachment as it appears secured to the needle.

Fig. 3 and Fig. 4 are opposite end views of the attachment on the needle.

Fig. 5 is a plan view of the parts as they 45 appear in Fig. 2.

Fig. 6 is an enlarged detailed vertical sectional view through the attachment and needle.

Fig. 7 is a vertical sectional view at 7—7 50 Fig. 6.

Fig. 8 is a plan view of the threader cone member as it would appear opened up and flattened.

55 Fig. 9 is an enlarged detailed end view of the cone shaped member.

In the drawing like characters of refer-

ence indicate corresponding parts in the several figures.

1 is the foot end of a sewing machine which presents the customary needle bar 60 2 carrying the needle 3 and the customary foot piece bar 4 carrying the foot piece 5.

The needle is detachably clamped to the needle bar in the usual manner, the winged clamping screw being indicated at 6. 65

I have not considered it necessary to give a detailed description of the former parts as they are well known and form no part of my invention.

The threading attachment which I provide 70 is detachably secured to the needle and comprises the following parts.

7 is a metallic body piece provided at one end with a vertical slot-like opening 8 which has the inner end rounded as indicated at 75 9 and the other end flat and the sides slightly bellying inward as indicated at 10.

At the outer end of the slot I locate a jam block 11 which is slidable in and out within the slot and is actually held within 80 the slot by having the upper and lower ends flared to accommodate the inwardly curving sides of the slot (see Fig. 7). This is a simple way of retaining the block in the slot, but of course, I do not desire to be 85 limited to the arrangement shown as this can be readily modified as will be readily understood.

The block 11 is engaged by an adjusting screw 13, screw threading through the body 90 7 and fitted with a head having a cross slot 14 therein so that it can be manipulated by a screw driver.

Obviously one can readily attach the body piece to the needle by passing the needle 95 through the inner end of the slot and then screwing in the screw 13 to cause the block 11 to jam the needle against the rounded end 9 of the body piece.

The upper corner of the body piece at the 100 end remote from the screw is partially cut away to provide a cross groove 15 somewhat in from the end of the body piece and which is approached by a curved face of an ogee shape, 16 is a spring over-hanging the groove 105 and the ogee face and secured to the body piece in any suitable manner. In the drawing this is accomplished by means of a screw 17, but if desired it can be permanently riveted to the body piece. 18 is a somewhat 110 cone shaped guide having a threading opening 19 formed at the peak of the cone mem-

ber, a pair of opposing lining tongues 20 and 21 positioned beneath the opening and a pair of fastening flanges 22 and 23 located on the under side.

- 5 Actually the cone shaped member is formed from a single piece of metal stamped initially in the shape shown in Figure 8. After being cut in this shape the blank is bent in to a more or less cone shape the 10 tongues being opposed and a thread release opening 24 being maintained at the bottom side. After being bent in to this latter shape the cone member is attached to an arm formed from a single length of stiff wire 15 looped to present two legs 25 and 26, the extremities of which are attached to the holder by means of the flanges 22 and 23 the flanges being actually rolled over the extremities of the wire which are bent sideways as 20 best shown in Figure 2. The loop end of the wire is bent into a position at right angles to the legs as shown at 27 and this looped part is inserted into the groove 15 between the spring 16 and the end of the body piece.
- 25 I desire that the free end of the spring move up to allow the loop to pass into position and that when it is in its final position the spring bear down on it sufficiently to prevent the legs from swinging freely.
- 30 When the device is in position on the needle the tongues 20 and 21 span the eye end of the needle and line the opening 19 of the threader with the eye of the needle. Consequently it is an easy matter to insert the end of a thread into the large end of 35 the cone member and shove it in until it passes through the opening 19 and into and through the needle eye. Once this is accomplished the thread is pulled down through 40 the slit reserve at 24 to free it from the threader and leave it threaded through the eye. One can then swing the legs upwardly

to a position as shown in dotted outline in Figure 1 or can remove the legs from the body piece 7 by pulling the loop forcibly 45 outwardly from between the spring and the body piece.

In case one encounters a long needle additional adjustment can be had by reversing or turning the body piece up side down to 50 bring the groove 15 underneath and then reversing the position of the legs. By so doing one gains the depth of the body piece which is actually added to the length of the legs 55 and can then make the final adjustment by the screw 13 on the needle. Whilst I have described the member as a cone shaped member I wish to be understood that this is not a true description of it as it only approximates a cone and actually the base of the cone 60 is cut away at a slant to allow of the easy insertion of the thread when one is threading the needle.

What I claim as my invention is:—

In a needle threading attachment for a 65 sewing machine a thread guide consisting of a split, horizontally disposed, conical body, having the split on the under side, the divided edges of the body being spaced apart and provided with spaced aligning extensions projecting beyond the small end of the body, horizontal sleeves carried by the opposite sides of the body, a supporting member 70 and a pair of vertically extending arms suspended from said supporting member and having the ends of the arms bent and entering the sleeves to support the cone body.

Signed at Winnipeg this 19th day of June, 1920.

DAVID ALEXANDER LIVINGSTON.

In the presence of—
G. S. ROXBURGH,
K. B. WAKEFIELD.
